UNITED STATES PATENT OFFICE.

EMIL PASSBURG, OF BERLIN, GERMANY.

VACUUM DRYING APPARATUS.

No. 853,260.

Specification of Letters Patent.

Patented May 14, 1907.

Application filed July 27, 1905. Serial No. 271,418.

To all whom it may concern:

Be it known that I, EMIL PASSBURG, a subject of the German Emperor, residing at Berlin, in Germany, have invented certain new and useful Improvements in Vacuum Drying Apparatus for the Production of Coarse-Grained Materials from Liquids, of which the following is a specification.

The invention relates to a vacuum drying apparatus for drying liquids in thin layers, on endless bands passing around heating bodies and the object is to obtain coarse grained or crystalline materials in a continuous automatic manner by fully utilizing the heating surfaces of said bodies, instead of the pulverized material, as obtained in known drying apparatus of similar kinds. This object is obtained by supplying the material to be dried from both sides on to the endless transport bands whereby owing to the rapid evaporation due to the vacuum, bubbles are formed which dry in this shape and drop by gravity at the point where the bands pass round their supporting and driving rollers, or are loosened by scrapers in such a manner that the coarse structure of the material is preserved and the formation of pulverized materials prevented. The heating body lies and the drying bands can be arranged in a horizontal or vertical direction as required.

In the accompanying drawing Figure 1 is a vertical section of a vacuum drying apparatus with vertical drying bands, Fig. 2 is a horizontal cross section through the casing upon a plane indicated by the line 2-2 in Fig. 1, showing the interior of the apparatus in plan with the scrapers *m* and the feed tubes *h* omitted. Figs. 3, 4 and 5 are detail views on an enlarged scale representing various means for bringing the liquid on to the drying bands, Fig. 6 is a vertical longitudinal section showing a vacuum drying apparatus with horizontal drying bands, Fig. 7 is a vertical cross section of Fig. 6, Figs. 8 and 9 are detail sections showing modifications of the rollers which carry the drying bands.

Referring to Figs. 1 and 2 the upright cylindrical drum or casing *V* forms the vacuum chamber, which surrounds the vertical plates *a* tubes *b* or other suitable heating means in which steam or hot water or another suitable heating medium such as hot air or the like is caused to circulate. The heated fluid may be introduced through such means as tubes *q* and may be discharged through tubes *r*. Endless bands *c* are mounted on pairs of ro-

tatable rollers *i* and *d* and are caused to travel on said rollers as close as possible past the heating devices *a* or *b*. The axles of the rollers may be driven by sprocket wheels *s* provided with chains *t* or by some other suitable means, from any suitable driving device (not shown).

For supplying the liquid to be dried to the bands, lower and upper distributing or feed tubes *e* and *h* respectively are used, which may receive liquid from supply tubes *u* and are either provided with small closely arranged holes or tubular nozzles *f* (Fig. 3) or slots with a filling of wick (Fig. 4) or without said filling (Fig. 5). The liquid flows from the openings on to the bands either in the form of drops or in a thin layer. The upwardly traveling surfaces of the bands are supplied with liquid by the lower distributing or feed tubes *e* and the downwardly traveling surfaces by the upper distributing or feed tubes *h*.

The drying bands may of course be driven at the particular rate of speed desired and the quantity of liquid supplied to the bands may be regulated by some such means as a valve *p*; so that when the liquid arrives at the rollers *i* or *d* as the case may be, it will be dried to the extent desired. At the point where these bands pass round the rollers the dried material is completely or partly loosened and falls and by means of scrapers *m* and *o* any dried material which may remain on the band is completely removed therefrom. On further movement of said bands they are at once again supplied with fresh liquid by the distributing tubes *e* and *h*.

Partitions *W* may be arranged between the bands to prevent the falling dried material from coming in contact with the bands charged with the liquid and for the same purpose the upper rollers *i* may be given a larger diameter than the lower rollers *d* (Fig. 8).

The dried falling material passes into the screw conveyer *S* and is removed therefrom either to undergo a supplementary drying in a drying cylinder with stirring apparatus or into a receptacle of known kind whence it is removed by known means with or without interruption of the vacuum in the drying apparatus.

In the apparatus shown in Figs. 6 and 7 the drying bands are arranged in horizontal planes. The liquid flows from a receptacle *l* through tubes *u* to the distributing or feed

tubes *e* and *h*, which distribute the liquid in drops or thin layers, to the upper surface of the drying bands *c*, which travel around the plates *a* or other heating bodies in the known manner. When the dried material falls at the point where the band *c* passes round the roller *d* the said band passing the distributing tubes containing the liquid is again supplied with liquid from below through the tubes *e*, the distribution being preferably effected in drops or in a thin layer. Instead of the distributing tubes *e* and *h* slot like openings can also be arranged from which the liquid flows in a thin layer and moistens the band. The drops or thin layers of previously concentrated and therefore thick or viscous liquid remain on the lower surface of the band *c*, owing to adhesion and form bubbles during the rapid evaporation by reason of the vacuum and when dried drop at the point where the band passes round the rollers *d* and *i*. In order that the bands *c* may pass the heating devices as closely as possible, the rollers *d* and *i* may be given a diameter slightly smaller than the height of said heating devices *a*. (Fig. 9) The band *c* and the heating bodies *a* may be arranged either vertically or horizontally in the casing.

I claim as my invention—

1. In a vacuum drying apparatus the combination of heating devices located side by side, rollers at the ends of these heating devices, an endless transporting band passing over each pair of rollers, and two feed tubes for the liquid to be dried on the transporting band, the feed tubes being located at opposite ends of and on opposite sides of the corresponding heating device, substantially as described.

2. In a vacuum drying apparatus, the combination of heating devices side by side, rollers at the ends of these heating devices, an endless transporting band passing over each pair of rollers, two feed tubes for the liquid to be dried on the transporting band, the feed tubes being located at opposite ends of and on opposite sides of the corresponding heating device, and a pair of scrapers for the removal of the dried material from each band substantially as described.

In testimony whereof I affix my signature in presence of two witnesses.

EMIL PASSBURG.
